MAGNETIC MEASURING TAPE

Lloyd J. Le Roue, Rte. 2, P.O. Box 2360,
Wapato, Wash. 98951

Filed Nov. 24, 1969, Ser. No. 20,254

Term of patent 14 years

Int. Cl. D10—08

U.S. Cl. D52—1

FIG. 1

FIG. 2

FIG. 3

FIG. 1 is a right front perspective view of the magnetic measuring tape embodying my new design;

FIG. 2 is a right front perspective view with tape and magnetic holder extended;

FIG. 3 is a side opposite FIG. 2 as viewed from the under portion.

I claim:

The ornamental design for a magnetic measuring tape, substantially as shown and described.
